CIRCUIT BREAKER

John B. MacNeill, Wilkinsburg, Pa., assignor to
Westinghouse Electric & Manufacturing Com-
pany, East Pittsburgh, Pa., a corporation of
Pennsylvania

Application February 20, 1937, Serial No. 126,898

15 Claims. (Cl. 200—50)

This invention relates to circuit breakers and more particularly to operating mechanisms therefor. The conservation of space generally in connection with the design of electrical apparatus, has, of late, been given more and more attention. Particular efforts to effect economy in space have been made in the design of circuit breakers adapted for the protection of relatively low voltage electrical networks. It is the usual practice in underground network systems to mount the low voltage circuit breakers or network protectors as they are commonly called, in a waterproof housing, which, in turn, are usually located in a manhole or underground vault. It is therefore readily apparent that in installations of this kind, the conservation of space is greatly to be desired. However, in carrying out this desideratum, there has resulted a circuit breaker, which, although compact in design, is impractical due to the difficulty experienced in servicing the contact structure.

The main object therefore of my invention is to provide a circuit breaker, the contact structure and operating mechanism of which are compact in design, but which are readily accessible for inspection and repair.

A further object of my invention is to provide a circuit breaker in which the operating mechanism is separable as a unit from the contact structure so as to render both the contacts and the operating mechanism accessible for inspection, without necessitating the disassembly of these parts.

A further and more specific object of my invention is to provide a circuit breaker in which the operating mechanism for the contact structure is mounted upon a hinged frame so as to be movable as a unit from an operative position in front of the contact structure to an inoperative position remote from the contact structure.

A still further object of the invention is to provide a swinging frame for mounting the operating mechanism of a circuit breaker as a unit, which frame also provides a highly accessible support for relays, auxiliary switches and other accessories necessary for the control and operation of the circuit breaker.

Other objects and advantages relate to details of the circuit breaker structure, and will appear more fully in the following description taken in connection with the accompanying drawings in which:

Fig. 1 is a perspective view of the circuit breaker of my invention, showing the hingedly

mounted operating mechanism in the open or inoperative position.

Fig. 2 is a front elevation view of the moving contact assemblage of the circuit interrupter of my invention.

Fig. 3 is a side elevation view, partially in cross section, showing the principal parts of the contact structure and the operating mechanism, and

Fig. 4 is a front elevation view of the operating mechanism, showing the panel carried by the hinged frame and the several auxiliary devices mounted thereon.

With particular reference to the drawings, the numeral 10 designates a base or panel of insulating material upon which the contact assemblage and frame units of the breaker structure are mounted. The fixed contacts for each of the three poles 12, 13 and 14 are secured to three main current carrying busses 15 mounted in spaced relation upon the insulating panel 10. The fixed contact and bus arrangement for one of the three poles is shown in Fig. 3. Each pole includes two of the contacts indicated at 12 spaced horizontally and one contact 13 positioned intermediate the contacts 12 but displaced vertically above the line joining the contacts 12. The contacts 14 are positioned in vertical alignment with the contacts 13. The movable contact arrangement shown more clearly in Figs. 30 2 and 3 comprises contacts 16, 17 and 18 adapted for respective cooperating engagement with the contacts 12, 13 and 14. The movable contacts 16, 17 and 18 are respectively mounted upon contact carrying members 19, 20 and 21. Each 35 of the contact carrying members 19 and 20 are connected by means of a laminated flexible conductor 23 to a fixed bus 25 mounted upon the insulating panel 10. The bus 25 for each pole is provided with a current transformer 27, which, 40 in turn, provides the necessary current for controlling the circuit breaker operation.

The movable contact structure for the three poles of the breaker is supported upon a contact arm 29 (Fig. 3) pivoted at 31 to a suitable support 33 secured to the panel 10. The upper portion of the contact arm 29 is provided with a C-shaped recess 35 which cooperates with a clamping member 36 for engaging two horizontally extending parallel bars 37. The clamping members 36 and the bars 37 are maintained in rigid engagement with the contact arm 29 by means of bolts 39. For the two outer poles adjacent the central pole the clamping members 36 cooperate with suitable clamping members 41 having 55

the same general configuration as the upper or head portion of the contact arm 29. In order to insulate the clamping members 36 and 41 of the various poles from each other, the support bars 37 are preferably covered with insulating material 42.

The contact carrying members 19 are pivotally connected at 45 to an eye-bolt 46, which, in turn, passes through the clamping members 41 of the two outer poles and the head portion of the contact arm 29 of the central pole. A coil spring 47, encircling the eye-bolt 46, positioned between the current carrying member 19 and the clamping member 41 biases the contact arm 29 away from the contact carrying members 19 and is limited in its biasing movement by adjusting nuts 48 secured to the end of the eye-bolts 46.

The centrally positioned contact carrying member 20 for each pole is pivotally coupled at 49 to an eye-bolt 52, and in turn biased from the clamping members 41 for the two outer poles and the head portion 53 of the contact arm 29 for the central pole, by springs 55. Movement produced by the biasing action of the spring 55 is limited by the adjusting nuts 56 secured to the end of the eye-bolts 52. It is thus seen that the contact members 19 and 20 are permitted to move relative to the contact arm 29 and due to the spring engagement between these contact carrying members 30 and the contact arm 29, an equalization of the contact pressure between the fixed contacts 12, 13 and the cooperating moving contacts 16, 17 is obtained.

Each of the clamping members 36 is provided with a pair of spaced downwardly projecting fingers 58 to which are pivotally supported, by means of rods 59, the bifurcated end of contact support members 21. The contact supporting member 21 is also biased from the clamping members 41 for the two outer poles and from the head portion 53 of the central pole, by coil springs 61, which, in each instance, are larger in diameter than biasing springs 55 and encircle the same.

The contact arm 29, in addition to the biasing action caused by the springs 47, 55 and 61, is also biased to the open circuit position by two accelerating springs 63, the upper ends of which are connected to the arm 29 and the lower ends secured to the bracket 33, as more clearly shown in Figs. 1 and 2.

During the opening operation of the contact structure, contacts 12 and 16 are first to separate, and are followed by contacts 13 and 17. The final break is obtained at the arcing contacts 14 and 18 from which contacts the arc is transferred by magnetic means to an arc extinguisher generally designated at 64.

The operating mechanism for moving the contact arm 29 to closed position is supported by a framework 71 (Fig. 1) having an upper hinge member 73 and a lower hinge member 74 adapted to be hinged, respectively, to corresponding hinge members 75 and 76 of the bracket 77 mounted upon the panel 10. The side of the frame 71 opposite the hinge members 73 and 74 is provided with a boss 78, having an aperture 83 therethrough for the reception of a stud bolt 79. The boss 78 is adapted to engage the boss 81 secured to a suitable bracket 82, also supported from the panel 10. The boss 81 has a threaded aperture 83 for the reception of the stud bolt 79 whereby the frame 71 is held in the secured or operative position with respect to the contact arm 29.

The operating mechanism supported within the

framework 71 consists of a pair of actuating arms 85 pivoted at their lower end by shaft 86 to suitable projections 87 of the frame 71. The upper ends of the actuating arms 85 are coupled to one end of a pair of toggle links 88 (Fig. 3) by means of shaft 89. The shaft 88 carries a roller 91 disposed between the toggle links 88, which roller is adapted to engage a bearing plate 92 mounted upon the face of the contact arm 29. The other end of the toggle links 88 is pivotally connected to one end of a second pair of toggle links 93 by the shaft 94. The other end of the pair of toggle links 93 is pivotally connected by a shaft 96 to a single linkage member 97 pivoted at 98 to the frame 71.

The linkage members 88, 93 and 97 provide a three-link toggle mechanism which, when in the made or closed position, is retained in that position by a positive latching mechanism comprising a latch member 101 pivoted to the frame 71 at 102 and having a U-shaped notch 103 for holding the latch roller 104, which, in turn, is journaled to the link member 97 at 105. The latch member 101 is held in the closed position by means of a latch toggle comprising a pair of toggle links 106 and 107 joined at 108 and having the link 106 pivoted to the latch member 101 at 109 and the link 107 pivoted to the frame 71 at 110.

The knee of the toggle linkage 106, 107 is adapted to rest in its over-center or made position against a stop 111 of the trip lever 112 which is also pivotally mounted to the frame 71 by the shaft 110. The trip lever 112 has a bearing surface 113 against which the operating plunger 114 of a shunt trip 115 is adapted to strike for the purpose of rocking the trip lever 112 about its pivot 116 to break the toggle 106 and 107.

After each tripping operation, the latch member 101 and the toggle 106, 107 are reset by means of spring 117 joining the latch member 101 and the toggle 107. The spring 117 is anchored at its respective ends in a position so that it moves the toggle 106, 107 to its over-center made position and the latch member 101 to its latching position, but does not bias the latch beyond the normal latching position. When the latching member 101 is in the latching position, and locked due to the latching toggle 106, 107, and the actuating linkage 88, 93, 97 is in the made or closed position, the pivotal points 94 and 96 are over-center with respect to the line joining the pivotal points 88 and 98. Inasmuch as the knee of the toggle formed by the links 88 and 93 have a bearing surface against the frame 71 at 98, and since the linkage member 97 is held in the latched position by the latching member 101, the force exerted by the contact springs 47, 55 and 61 through the contact arm 29 bearing against the roller 91 will tend to cause the latching linkage member 97 to rotate in a clockwise direction. The tendency for member 97 to rotate is opposed by the bearing surface 119 of the latch member 101 engaging the latching roller 104.

The point of contact of the latching roller 104 with the surface 119 is such that there is a small moment arm about the pivotal axis 102 of the latch arm 101. This moment arm tends to produce rotation of the arm 101 in the counter-clockwise direction, but when in the latched position is resisted by the toggle 106, 107. Thus, when it is desired to trip the breaker mechanism, through means energizing the shunt trip element 115, the operation is as follows: The shunt trip rod 114 engages the bearing surface 113, lifting the trip lever 112, rocking it about its pivot 116

in the clockwise direction, causing the bearing surface 111 thereof to engage the knee of the toggle 106, 107 and to move this toggle to the broken position. Breaking the toggle 106, 107 5 rotates the latching member 101 about its pivotal axis 102, thereby releasing the latch roller 104, which, in turn, permits the link 97 to rotate in a clockwise direction about its pivotal axis 98, so that the pivot 96 is carried upwardly and to the 10 right, thereby causing the pivotal axis 94 between the linkage 88, 93 to be displaced downwardly with respect to the line joining the axis 88 and 93. As soon as the linkage member 97 begins 15 its clockwise rotation, the actuating arm 85 is rocked to the right in a clockwise direction, permitting movement of the contact arm 29 towards the open position. This movement is accelerated by the almost simultaneous operation of the 20 toggle linkage 88, 93. As soon as the linkage 88, 93 is broken and the tripping force is removed from the trip lever 112 the spring 117 immediately restores the latch toggle 106, 107 and the linkage member 97 to their normal or set positions. More specifically, the resetting of the link member 97 is accomplished by the curved surface 121 of the latch member 101 engaging the latching roller 104 and causing the linkage member 97 to be rotated in a counter-clockwise direction until the latching roller drops it to the U-shaped 25 notch 103.

In order to reclose the breaker, two agencies are provided. In the event the automatic operation is to be desired, I have provided a driving motor 125 mounted upon the lower portion of the 30 frame 71 and coupled through a worm and worm gear enclosed in a casing generally shown at 127, to a crank arm 128 secured to the shaft 129. The end of crank arm 128 is provided with a closing roller 130, which is adapted to engage an arcuate 35 notch 131 of an actuating arm 133, the upper end of which has pivotal engagement with the shaft 94 joining the toggle links 88 and 93. The lower end of the actuating link 133 is provided with a 40 guide stud 134 adapted, for engagement in a curved guide slot 135 positioned in guide plate 45 136 secured to the side of gear casing 127.

When the contact arm 29 is in the open circuit position and the toggle linkage 88, 93 is in the broken position, the actuating link 133 will be in its lowermost position, so that the guide stud 134 will be adjacent the lower end of the guide slot 135. It will be apparent that as the crank arm 128 is rotated in a counter-clockwise direction, the closing roller 130 will engage the arcuate 50 notch 131 and carry the actuating link 133 upwardly so as to move the toggle linkage to the made position, thereby causing roller 91 to engage the bearing plate 92 of the contact arm 29 and move the latter to the closed circuit position. 55 When the toggle linkage 88, 93 is moved to the made position, the link members 93 engage an operating rod 140, which, in turn, engages a lever 141 of a cut-off switch 142 connected in the control circuit of the motor 125. Thus, when the 60 toggle linkage 88, 93 is in the made position, switch 142 is thrown to the "off" position, thereby cutting off the supply of current to the operating motor 125.

The notch 131 of the actuating link 133 is so 65 disposed with respect to the closing roller 130 that, upon the toggle linkage 88, 93 reaching its made position, the roller 130 continues its path of movement and becomes disengaged from the notch 131. In order to prevent undue motion of 70 the motor and driving mechanism after the power has

been cut off by means of the snap switch 142, the motor 125 may be provided with a break mechanism indicated at 145, which may be of a centrifugal or other suitable type.

Manual means for closing the breaker are also provided and comprise a shaft 150 journaled in brackets 177 and 151 supported by the panel 18. The shaft 150 has a crank arm 153 secured thereto, which arm is provided with a roller 155 which roller is adapted to engage the arcuate end 156 of the manually operable actuating link 157, the upper end of which is journaled to the shaft 94 coupling the toggle linkage 88, 93. The actuating link 157 is biased to the roller engaging position by a spring 158.

The outer end of the manually operated shaft 150 is provided with a male clutch member 160 adapted to be engaged by a suitable female clutch member forming part of an operating handle whereby the shaft 150 may be rocked in a counter-clockwise direction to move the toggle linkage 88, 93 to the made position. The crank arm 153 is also provided with a projection 162 which is adapted to be moved into engagement with one end of an auxiliary trip lever 163. The auxiliary trip lever 163 is shown pivoted at 164 and has its opposite end terminating in a bearing surface 165 which forms a stop for the bearing surface 113 of the trip lever 112. An adjusting screw 166, carried by the bracket 167, provides an adjustable stop surface for adjusting the position of the auxiliary trip lever 163 and the main trip lever 112.

In order to prevent opening the hinged frame 71, or, in other words, from swinging the operating mechanism to the inoperative position, at times when the breaker contacts are in the closed position, an interlock between the trip mechanism and the securing means for holding the frame 71 in the fixed position is provided. 35 This interlock consists of a covering member 170 pivoted at 171 to the boss 81 and having a transverse portion 172 normally extending in covering relation across the head of the stud 79 which retains the frame 71 in the closed position. The 40 covering member 170 is connected by an actuating member 173 to a crank 174 secured to the manual operating shaft 150. The crank 174 is so positioned upon the shaft 150 with respect to the crank 153 that the covering member 170 45 permits access to the stud 79 only when the projection 162 of the crank arm 153 is in engagement with the auxiliary trip lever 163. Thus, in order to remove the stud 79, it becomes necessary to operate the manual control lever to the tripped 50 position causing the arm 162 to engage the auxiliary trip lever 163 which, in turn, actuates the main trip lever 112 to cause the breaker contacts to be tripped to the open position in a manner 55 previously described.

After the breaker has been tripped in the manner just described by rotating the shaft 150 in a clockwise direction, the stud 79 may be removed and the frame 71, and the operating mechanism supported thereby, may be swung to 60 the open position, thus permitting ready access to the contact mechanism for inspection or repair.

As more particularly shown in Fig. 4, the frame 71 is provided with a panel 180 which is adapted 65 to be rigidly secured to the frame and to be movable therewith. Upon the panel 180 may be mounted suitable relays as generally indicated at 181, 182 and 183 for the control of the various switching operations. The panel 180 may also 70

be utilized for mounting auxiliary control switches indicated generally at 185. The switches 185 in this instance may be actuated by an operating rod 186 connected to a bell crank 187 pivoted at 188, which, in turn, is connected by an actuating member 189 to the actuating arm 85. It will be apparent that when the actuating arm 85 is moved to the open circuit position, connecting member 188 will rock bell crank 187 in a clockwise direction about its pivot 188, causing the actuating member 186 to actuate the switches 185. The actuating member 186 may also be coupled by a suitable link 191 to a semaphore 192 pivoted to the supporting panel 180 at 193. The semaphore 192 may have colored windows 194 of different colors adapted to be moved, respectively, in front of an indicating lamp 195. Thus the lamp in projecting light through the colored windows 194, will indicate the open and closed position of the breaker in accordance with a predetermined color code.

It will be understood from the foregoing that although I have shown and described a particular breaker structure embodying a specific contact arrangement, and have shown and described a particular operating mechanism whereby the breaker contacts are moved to open and closed position, it is to be understood that the details of construction are for illustrative purposes only, and that other contact and operating mechanisms may be adapted to be arranged for relative movement with the operating mechanism as a whole, without departing from the spirit and scope of the appended claims.

35. I claim as my invention:

1. A circuit breaker comprising a fixed contact, a contact arm, a movable contact carried by said contact arm and adapted to be moved thereby into and out of contacting engagement with said fixed contact, a frame mounted for swinging movement about a fixed pivot, and operating mechanism supported upon said frame for operating said contact arm to open and closed positions, said operating mechanism including a toggle linkage movable to made and broken positions to respectively move said contact arm to closed and open positions, and latching means for releasably retaining the toggle linkage in the made position, releasable means for securing said frame in a fixed position to render said operating mechanism operative with respect to said contact arm, and movable means interlocked with said latching means for preventing the release of said securing means when the contact arm is in the closed position.

2. A circuit breaker comprising relatively movable contact means, electric operating means for said contact means, a support means for said operating means movable to position said operating means in complete operative engagement with said contact means and to position said operating means away from said contact means.

3. A circuit breaker comprising a support, relatively movable contact means mounted on said support, said contact means being biased to open circuit position, a frame relatively movable with respect to said support, a complete operating mechanism carried by said frame including an operating member mounted for operating movement in a single plane for operating said contact means, said frame being movable to position said operating mechanism with its operating member in complete operative driving relation to said contact means, and to position said oper-

ating means and operating member away from said contact means.

4. A circuit breaker comprising a support, relatively movable contact means mounted on said support, said contact means being biased to open circuit position, an electric operating mechanism including an operating member mounted for operating movement in a single plane for operating said contact means, a frame for supporting said operating mechanism pivotally mounted on said support for swinging movement to position said operating mechanism with its operating member in operative driving relation to said contact means and to position said operating mechanism and operating member away from said contact means.

5. A circuit breaker comprising a support, relatively movable contact means mounted on said support, a frame relatively movable with respect to said support, and operating mechanism carried by said frame including an operating toggle linkage for operating said contact means, said frame being movable to position said operating mechanism in operative driving relation to said contact means and to position said operating mechanism away from said contact means.

6. A circuit breaker comprising a support, relatively movable contact means mounted on said support, said contact means being biased to open circuit position, a frame relatively movable with respect to said support, a complete operating mechanism for said contact means carried by said frame, said frame being movable to an operative position in which said operating mechanism is disposed in complete operative driving relation to said contact means and in which access to said contact means is prevented, and movable to an inoperative position in which said frame and operating mechanism are away from said contact means to permit access to said contact means.

7. A circuit breaker comprising a support, relatively movable contact means mounted on said support, a frame relatively movable with respect to said support, operating mechanism carried by said frame for operating said contact means including electric means for operating said mechanism, said frame being movable to a position in which said operating mechanism is disposed in complete operative driving relation to said contact means, and to a position in which the frame and operating mechanism are away from said contact means.

8. A circuit breaker comprising a support, relatively movable contact means mounted on said support, a frame relatively movable with respect to said support, a complete operating mechanism carried by said frame for operating said contact means including a tripping means operable in response to predetermined conditions to cause said mechanism to open said contact means, said frame being movable to a position in which said operating mechanism is disposed in operative driving relation to said contact means and to a position in which the frame and operating mechanism are away from said contact means.

9. A circuit breaker comprising a support, relatively movable contact means mounted on said support, a frame relatively movable with respect to said support, operating mechanism carried by said frame including means operable to close said contact means and tripping means operable to cause said mechanism to effect opening of said contact means irrespective of the position of said closing means, said frame being movable to an

operative position in which said operating mechanism is disposed in complete operative relation to said contact means, and to a position in which the frame and operating mechanism are away from said contact means.

10. A circuit breaker comprising a support, relatively movable contact means mounted on said support, a frame relatively movable with respect to said support, operating mechanism carried by said frame including trip means operable to cause said mechanism to open said contact means, said frame being movable to an operative position in which said operating mechanism is disposed in complete operative relation with said contact means, and to an inoperative position in which the frame and mechanism are away from said contact means, and means operable to prevent movement of said frame away from its operative position when said contact means are in closed circuit position.

11. A circuit breaker comprising a support, relatively movable contact means mounted on said support, a frame relatively movable with respect to said support, operating mechanism carried by said frame including trip means operable to cause said mechanism to open said contact means, said frame being movable to an operative position in which said operating mechanism is disposed in operative relation with said contact means, and to an inoperative position in which the frame and mechanism are away from said contact means, and movable means interlocked with said mechanism operable to prevent movement of said frame away from its operative position when said contact means are in closed circuit position.

12. A circuit breaker comprising a support, relatively movable contact means mounted on said support, a frame relatively movable with respect to said support, operating mechanism carried by said frame including trip means operable to cause said mechanism to open said contact means, said frame being movable to an operative position in which said operating mechanism is disposed in operative relation with said contact means, and to an inoperative position in which the frame and mechanism are away from said contact means, and means interlocked with said trip means operable to prevent movement of said frame away from its operative position when said contact means are in closed circuit position.

13. A circuit breaker comprising a support, relatively movable contact means mounted on

said support, a frame relatively movable with respect to said support, operating mechanism carried by said frame for operating said contact means including tripping means operable in response to predetermined conditions to cause said operating mechanism to open said contact means, said frame being movable to an operative position in which said operating mechanism is disposed in operative relation to said contact means and to an inoperative position in which the frame and operating mechanism are away from said contact means, means releasably securing said frame in operative position, and movable means interlocked with said operating mechanism for preventing release of said securing means when said contact means are in closed circuit position.

14. A circuit breaker comprising a support, relatively movable contact means mounted on said support, a frame relatively movable with respect to said support, operating mechanism carried by said frame for operating said contact means, said frame being movable to an operative position in which said operating mechanism is disposed in operative relation to said contact means and to an inoperative position in which the frame and operating mechanism are away from said contact means, releasable means for securing said frame in operative position, trip means operable to cause said operating mechanism to effect opening of said contact means, and movable means interlocked with said trip means for preventing release of said securing means when said contact means are in closed circuit position.

15. A circuit breaker comprising a support, relatively movable contacts mounted on said support, a switch member movable to open and to close said contacts, said switch member being biased to open said contacts, a frame movable relative to said support, operating mechanism for said switch member carried by said frame, said mechanism including an actuating member separably engageable with said switch member and movable to open and to closed position by said mechanism to cause opening and closing of said contacts, said frame being movable to a position in which said actuating member and mechanism are disposed in complete operative engagement with said switch member and to a position in which said actuating member and mechanism are away from said contact means and switch member.

JOHN B. MACNEILL.
